UNITED STATES PATENT OFFICE.

DAVID J. SCOTT, OF PLAINFIELD, NEW JERSEY, ASSIGNOR TO ISABELLA SCOTT AND DAVID J. SCOTT, EXECUTORS OF THE ESTATE OF WALTER SCOTT, DECEASED, DOING BUSINESS AS WALTER SCOTT & COMPANY, OF PLAINFIELD, NEW JERSEY.

ROLL-CHANGE DEVICE.

Application filed March 25, 1926, Serial No. 97,169. Renewed November 7, 1928.

This invention relates to a roll change device of the character used in connection with web pulling, such as printing, machines and has for its main object and feature the provision of means whereby a roll change may be more readily effected than heretofore.

In the prior art of roll change devices it has been the custom to employ a rotatable support in which are mounted a plurality of web rolls, usually three, and means are provided for rotating said support to bring the rolls successively into action, the leading end of the replenishing roll being pasted and the movement of the support bringing the pasted roll into contact with the employed web. This construction has several disadvantages, the chief one being the necessity of moving the heavy support or roll stand during the pasting action and also that if the paste does not happen to be in the right place on the roll the pasted portion may move by the employed web and consequently no joining of the webs takes place.

These disadvantages are obviated in the present invention in that, instead of pasting a roll to a web, guiding means are provided for independently guiding the two webs in the same general direction and adjacent to each other so that the two webs may be attached together whether the support is moving or standing still, and, when moved, the support is rotated in the same general direction as that of the feeding movement of the webs unwinding from the rolls.

In the accompanying drawings the invention is disclosed in a concrete and preferred form in which:

Fig. 1 is a general view, somewhat diagrammatic, in end elevation, of a machine embodying the invention.

Fig. 2 is a detail view, in end elevation, of the pasting means.

Fig. 3 is a side elevation of the parts shown in Fig. 2.

Fig. 4 is a detail view showing a modification.

1 indicates a web-pulling machine such as a printing machine and 2 is a rotatable support mounted on shaft 3 and adapted to hold a plurality of rotatable web rolls, in the present instance three, designated by 4, 5 and 6. Roll 4 is the employed roll and 5 and 6 are replenishing rolls. Employed web 7 from roll 4 passes over guides 8 and 9 and

thence through the rollers of an automatic tension device 10 of the character disclosed in application Ser. No. 741,098, filed October 2, 1924, after which it enters the web-pulling machine. 11 indicates a backing member of a flexible character here consisting of a belt 12 passing over pulleys 13 and 14. Pulley 14 is mounted in a sliding bearing 15 and spring 16 normally urges said bearing downward in Fig. 2, but when pressure is applied to the belt during the pasting action the sliding bearing will move up to compensate for the flexing of one of the normally straight runs of the belt. As shown, this backing member is located intermediate guides 8 and 9.

17 indicates a web-attaching member or pasting roller located adjacent the backing member but with the employed web intervening, and this roller, as here shown, is mounted on a crank arm 18 on shaft 19. 20 is a handle for actuating the crank arm. 21 indicates a replenishing web coming from roll 5 and threaded over said roller 17 so that it lies adjacent to the employed web. 22 is a pasting shelf on which the end of the replenishing web is placed and where it may be held in position by grippers or spring fingers 23. When the end of web 21 is on the shelf 22 paste may be applied to it.

It will be noted that the arrangement of the parts is such that the replenishing web may be threaded over the pasting roller while web 7 is feeding. When roll 4 is about to become exhausted, web 21 having been threaded into position and pasted as previously described crank arm 18 is swung upward to the right in Fig. 1 thereby drawing the end of the replenishing web from under grippers 23 and bringing said replenishing web against the employed web and the latter against the backing member whereby the two webs are pasted together. The paste roller gives a wiping contact in the same general direction as the feeding movement of web 7, and belt 12 is fixed by the impact thereof in the manner described. Web 7 may be either standing still or running slowly while this action takes place and support 2 may likewise be either standing still or moving. Be that as it may, it will be seen that the turning movement of the support is likewise in the same general

direction as that of the feeding movement of the webs as they unwind from the rolls, this movement being indicated by arrow 24. The support may be turned by hand or by 5 means of a suitable motor acting through worm 25 and gear 26. So likewise crank arm 18 may be moved by hand or by means of a motor. After the joint has been made the old web is severed by hand or automatically 10 in a manner well understood.

In Fig. 4 is shown a modified form of the invention. Here the pasting shelf 22 is omitted and pasting roller 27 is in the form of a sector. The replenishing web has paste 15 applied to it either before or after placing the web over the pasting roller. The roller is then moved as previously described thereby pasting the two webs together, and, if the employed web is moving, the roller is 20 preferably moved at a greater rate of speed than that of the employed web.

I claim:

1. A roll change device including: a rotatable support for a plurality of rotatable 25 web rolls, one an employed and another a replenishing roll, a backing member adjacent which the web from the employed roll passes, means for so threading the web from the replenishing roll that a portion thereof lies adjacent said backing member with the web from the employed roll intervening whereby the webs from the employed and replenishing rolls may be attached together.

35 2. A roll change device including: a rotatable support for a plurality of rotatable web rolls, one an employed and another a replenishing roll, a backing member adjacent which the web from the employed roll passes, means for so threading the web from the replenishing roll that a portion thereof lies adjacent said backing member with the web from the employed roll intervening whereby the webs from the employed and replenishing rolls may be attached together, and means for turning the support in the same general direction as that of the feeding movement of the employed web adjacent the backing member.

45 3. A roll change device including: a rotatable support for a plurality of rotatable web rolls, one an employed and another a replenishing roll, a backing member adjacent which the web from the employed roll passes, means for so threading the web from the replenishing roll that a portion thereof lies adjacent said backing member with the web from the employed roll intervening whereby the webs from the employed and replenishing rolls may be attached together, and means to move the replenishing web against the employed web and the latter against the backing member.

55 4. A roll change device including: a rotatable support for a plurality of rotatable

web rolls, one an employed and another a replenishing roll, a backing member adjacent which the web from the employed roll passes, means for so threading the web from the replenishing roll that a portion thereof lies adjacent said backing member with the web from the employed roll intervening whereby the webs from the employed and replenishing rolls may be attached together, means for turning the support in the same general direction as that of the feeding movement of the employed web adjacent the backing member, and means to move the replenishing web against the employed web and the latter against the backing member.

5. A roll change device including: a rotatable support for a plurality of rotatable web rolls, one an employed and another a replenishing roll, a backing member adjacent which the web from the employed roll passes, means for so threading the web from the replenishing roll that a portion thereof lies adjacent said backing member with the web from the employed roll intervening whereby the webs from the employed and replenishing rolls may be attached together, a pasting roller mounted adjacent the backing member but with the webs intervening, and a crank arm to cause the pasting roller to move the replenishing web against the employed web and the latter against the backing member with a wiping movement in the same general direction as that of the feeding movement of the employed web adjacent the backing member.

6. A roll change device including: a rotatable support for a plurality of rotatable web rolls, one an employed and another a replenishing roll, a backing member adjacent which the web from the employed roll passes, means for so threading the web from the replenishing roll that a portion thereof lies adjacent said backing member with the web from the employed roll intervening whereby the webs from the employed and replenishing rolls may be attached together, means for turning the support in the same general direction as that of the feeding movement of the employed web adjacent the backing member, a pasting roller mounted adjacent the backing member but with the webs intervening, and a crank arm to cause the pasting roller to move the replenishing web against the employed web and the latter against the backing member with a wiping movement in the same general direction as that of the feeding movement of the employed web adjacent the backing member.

7. A roll change device including: a rotatable support for a plurality of rotatable web rolls, one an employed and another a replenishing roll, a backing member adjacent which the web from the employed roll passes, means for so threading the web from the replenishing roll that a portion thereof lies

adjacent said backing member with the web from the employed roll intervening including a pasting roller and a pasting shelf, and a crank for withdrawing the replenishing web from the shelf and bringing it against the employed web in the plane of the backing member.

8. A roll change device including: a rotatable support for a plurality of rotatable web rolls, one an employed and another a replenishing roll, a backing member adjacent which the web from the employed roll passes, means for so threading the web from the replenishing roll that a portion thereof lies adjacent said backing member with the web from the employed roll intervening including a pasting roller and a pasting shelf, a crank for withdrawing the replenishing web from the shelf and bringing it against the employed web in the plane of the backing member, and means for turning the support in the same general direction as that of the feeding movement of the employed web adjacent the backing member.

9. Web-attaching means including: a backing member adjacent which the web from an employed roll passes, a pasting roller, adjacent the backing member but with the employed web intervening, over which passes, adjacent the employed web, a replenishing web, a pasting shelf to receive the leading end of the replenishing web, and a crank arm to cause the pasting roller to move the replenishing web against the employed web in the plane of the backing member with a wiping movement in the same general direction as that of the feeding movement of the employed web adjacent the backing member.

10. A roll change device including: a rotatable support for a plurality of rotatable web rolls, one an employed and another a replenishing roll, means for independently guiding webs from both rolls in the same general direction and adjacent to each other so that they may be attached together whether the support is standing still or moving, and means for turning the support in the same general direction as that of the feeding movement of the webs unwinding from the rolls.

11. A roll change device including: a rotatable support for a plurality of rotatable web rolls to be successively employed, and means for unwinding the webs from the rolls with a feeding movement having the same general direction as that of the rotatable support.

12. Web attaching means including: a backing member adjacent which the web from an employed web roll passes and extending longitudinally of said web, a pasting roller, adjacent the backing member but with the employed web intervening, over which passes, adjacent the employed web, a replenishing web, a pasting shelf to receive the leading end of the replenishing web, and means to cause the pasting roller to move along said backing member in the same general direction as that of the feeding movement of the employed web, and to move the replenishing web against the employed web in the plane of the backing member.

Signed at Plainfield, in the county of Union and State of New Jersey, this 16th day of March, 1926.

DAVID J. SCOTT.
